UNITED STATES PATENT OFFICE.

WALTER M. AUSTIN, OF ZELIENOPLE, PENNSYLVANIA.

TRANSFORMER.

1,105,014.

Specification of Letters Patent.

Patented July 28, 1914.

Application filed February 23, 1911. Serial No. 610,400.

To all whom it may concern:

Be it known that I, WALTER M. AUSTIN, a citizen of the United States, residing at Zelienople, in the county of Butler and State 5 of Pennsylvania, have invented new and useful Improvements in Transformers, of which the following is a specification.

This invention relates to alternating current transformers, otherwise known as static 10 transformers, and has for one of its objects to reduce the weight and the cost of construction.

Another object is to provide an improved 15 construction of the above character having increased efficiency and durability.

As is well known, the principal parts of a transformer are the core and the coil or coils surrounding the core, the core being usually built up out of sheet iron laminæ approxi- 20 mately rectangular in shape.

In alternating current transformers, the core losses are proportional to the length of the mean magnetic circuit where the sectional area of the core and its maximum 25 density of magnetization are constant and the coil losses are proportional to the mean length of the coil turns where the sectional area of the coils and the current density are constant, so that the efficiency of the trans- 30 former may be increased by shortening the magnetic circuit or by shortening the mean length of turns in the coils, it being under- 35 stood that the coil turns must be long enough to surround the core and that the core must be long enough to envelop the coils.

In designing a transformer, due regard must also be had to practical and economical methods of manufacture and to the pro- 40 vision of effective ventilation. Laminæ having a circular shape would provide the shortest magnetic circuit for a given area but this shape is undesirable for various reasons, such as the waste of material in 45 punching and the difficulty in assembling the core on the coils. According to my invention, I propose to employ the laminæ of hexagonal configuration, which have almost as short a magnetic circuit as 50 a circular area, while permitting the same to be punched out of a sheet with little or no waste of material. The hexagonal shape of the lamina thus provides for constructing a core having

nearly the minimum perimeter for a given 55 area and consequently having a magnetic circuit correspondingly approaching a minimum length.

In connection with the construction of 60 transformers of the larger sizes, where the cost of material is more important than the cost of labor, another feature of my invention is to construct the core of laminæ 65 so arranged that circular coils may be employed, the advantage of circular coils being that the length of the coil turns is considerably less than that of coils of other shapes, for a given cross sectional area of core. Another advantage of a circular coil 70 is the lower cost of winding and furthermore, a circular coil is more durable than one with angular turns because the latter tends to bind very tightly on the corners of the core, thus endangering the coil insulation, while lying loosely on the flat sides of 75 the core, which latter naturally increases the sectional area of the coils.

In the accompanying drawing; Figure 1 is a transverse sectional view of a trans- 80 former embodying one form of my invention; Fig. 2 an elevational view thereof; Fig. 3 a transverse sectional view of a trans- 85 former embodying a slightly modified form of my invention; Fig. 4 an elevational view thereof; Fig. 5 a plan view of a transformer 90 core, showing one method of building up the core; Figs. 6 and 7 similar views, showing different methods of building up cores for three phase transformers; Figs. 8, 9, and 10, views of sheet metal blanks, showing 95 methods of punching the core laminæ to avoid waste of material; Fig. 11 an elevational view of a transformer embodying my invention in which circular coils are employed; Fig. 12 a plan view of one of 95 the laminæ employed in the construction shown in Fig. 11; Fig. 13 a section on line $x-x$ of Fig. 12, Fig. 14 a plan view of a slightly modified core construction embodying my improvement; and Fig. 15 a 100 view of a sheet metal blank, showing the manner of punching the core sections shown in Fig. 14.

According to the construction shown in Figs. 1 and 2, the transformer core is built 105 up of laminæ each comprising a punching 1 and two punchings 2, the punchings being alternated in the successive layers so as to

break joints. The core is built around the coil in the usual manner.

In Fig. 9 is shown a sheet metal blank with the punchings 1 and 2 marked out thereon, to indicate how the sheet is punched to provide the punchings without waste of material, or punching 2 may be blanked as shown in Fig. 10.

In Figs. 3 and 4, the legs of the core are not joined together, as shown in Fig. 1 but are separate and each leg is built of laminae, each lamina comprising a punching or element 2 and a punching or element 3, the manner of punching these sections without waste being shown in Fig. 9, or a punching 1 may be cut so as to make two punchings 3. The first lamina is formed of an element 2 and an element 3 having their ends abutting to form a hexagon, and the next lamina is applied with an element 3 superimposed on element 2 of the first lamina, so as to break joints.

In Fig. 5 is shown one leg of a transformer core built up entirely of punchings 3 to form a pieced together helix in the following manner: A punching 3 is first placed in position and then a second punching 3 is applied with one end thereof abutting one end of the first punching so that, as each punching 3 extends more than halfway around, the opposite end of the second punching will be displaced by and overlap the adjacent end of the first punching. A third punching 3 is then applied with one end abutting the overlapping end of the second punching, and so on, thus forming a pieced together helix. It will be noted that by this method of construction the number of joints for a given length of core is reduced as compared with the constructions shown in Figs. 1 and 3.

Fig. 6 illustrates a transformer construction for a three phase transformer in which each lamina is composed of one punching 1, one punching 3, and three punchings 2, the three coils *a—a*, *b—b*, and *c—c* of the different phases being situated as shown.

In Fig. 7 is shown another arrangement of laminae for a three phase transformer in which each lamina is composed of three punchings 4 and six punchings 5, the punching 5 being the same as the punching 3 except that it has one corner clipped off as shown at 20 in Fig. 9. The method of punching the sections 4 is shown in Fig. 8.

In order to employ circular coils the transformer may be constructed as shown in Fig. 11. According to this construction, each lamina is made as shown in Figs. 12 and 13, one punching 8 being similar to punching 3 but having one side bent in the form of an involute curve, as shown at 10 in Fig. 13. The curve is made involute so that the lamina will fit snugly together at the curve, by reason of the well known char-

acteristic of the involute curve. A circular hole is left in the center when the laminae are fitted together and the curve of the bent ends is the involute, preferably of said circular hole, although if desired the hole through the core may be larger than the circle of the involute.

Each lamina is completed by a punching 2 and a number of such laminae are built up to form each leg of the core. The desired number of legs are arranged in radial position, surrounding the coil, as shown in Fig. 14, the curve of the outer lamina of one leg closely fitting the curve of the outer lamina of the adjacent leg by reason of the involute shape.

The construction shown in Fig. 11 is particularly adapted for large transformers by reason of the large radiating surface provided and the economy of material employed, and as before stated, the circular coil has certain advantages over the rectangular coil. If desired, two sides of a hexagonal core punching may be made longer, so as to construct the core as shown in Fig. 14, and the punchings may also be blanked without waste of material, as will be evident from Fig. 15.

In designing the transformer core, the length of the sides of the hexagonal contour are preferably made twice the length of the sides of the hexagonal opening through the lamina, so that in punching from the sheet, there will be no waste of material. When the hexagon is not regular, as shown in Figs. 14 and 15 the width of the openings are made equal to one half the outside width, but the openings may be made as long as desired and still permit the punchings to be cut out without waste of material.

It is understood that I do not confine myself to the use of laminae that can be punched entirely without waste, as there may be times when it will be of advantage to use punchings of hexagonal shape, but of different proportions, such that there might be some waste of material.

Having now described my invention, what I claim as new and desire to secure by Letters Patent, is:

1. A lamina for a transformer core having a hexagonal contour and a hexagonal aperture the short diameter of which is equal to one half of the short diameter of the lamina, said lamina being formed of two elements, one having two sides and the other four sides of the hexagonal contour.

2. A lamina for a transformer core having an outer hexagonal contour and an aperture having a hexagonal contour symmetrical with the outer contour and having the distance between the two contours equal to one fourth the diameter of the lamina measured at right angles to the axis of sym-

metry of the lamina, said lamina being formed of two blanks, one constituting two and the other four sides of the lamina.

3. A laminated transformer core having 5 radial legs, the laminae forming the legs each having a curved end adapted to fit snugly against the curved end of the adjacent lamina.

4. A transformer core having radial legs 10 composed of laminae, each lamina having one end bent to an involute curve to permit the bent ends of the laminae to fit snugly together and form a hollow cylinder.

5. A transformer core composed of radial 15 legs formed of laminae each having one end

bent to the form of an involute curve, said bent ends being adapted when the core is built up to form a hollow cylindrical core.

6. A transformer core composed of radial legs formed of laminae each having one end 20 bent, the bent ends of the laminae being fitted together to leave a central circular hole and the ends of the laminae being bent to the involute of said circular hole.

In testimony whereof I have hereunto set 25 my hand.

WALTER M. AUSTIN.
